UNITED STATES PATENT OFFICE.

WILLIAM C. MORRILL, OF NEW YORK, N. Y.

LIQUID-DISPENSING DEVICE.

1,235,913.

Specification of Letters Patent. Patented Aug. 7, 1917.

Application filed February 9, 1915. Serial No. 7,095.

To all whom it may concern:

Be it known that I, WILLIAM C. MORRILL, a citizen of the United States, residing in the city of New York, borough of Manhattan, county and State of New York, have invented a certain new and useful Liquid-Dispensing Device, of which the following is a specification.

This invention is a liquid dispensing device, the same being adapted for use, more particularly, in connection with a container wherein liquid soap is stored free from contact with air in order to preclude deterioration and coagulation of the liquid material.

In my prior Patent No. 911,834, granted Feb. 9, 1909, there is disclosed a form of soap machine embodying a container, usually of glass, and a delivery device positioned at the bottom portion of said container and operable by an upward movement of the hand, said delivery device acting, mainly, to forcibly eject a limited predetermined quantity of the liquid material directly into the palm of the hand. Said delivery device as disclosed in said patent embodies a chambered body within which operates a piston adapted to control the flow of the liquid material into the space below it and to forcibly eject said material, said piston being normally depressed by a spring and being provided with a depending stem, the latter serving as a means for operating the piston at will and as a cut-off or valve when the piston is raised.

The delivery device of the aforesaid patent is composed of machined metal parts which are, comparatively speaking, expensive of manufacture.

My present invention embodies a construction, certain parts of which are composed of stamped or spun metal, thereby securing economy of manufacture, one of said sheet metal parts being so connected to the glass container as to afford protection to the fragile material of said container, thus minimizing the breakage thereof and imparting a desired finish to the machine.

More specifically speaking, the present invention embodies a closure or head composed

of sheet metal and provided at its perimeter with a flange and at its center with a depending tubular boss, combined with a piston having a stem depending through a delivery opening provided centrally in said tubular boss, and a sleeve, the latter being separate from the closure and attached in a suitable way to said closure head so as to coöperate with the piston and the pressure spring for said piston. Said sleeve performs several important functions, *i. e.* it is positioned for frictional contact with the piston, thus acting as a guide for said piston in the vertical travel thereof; it houses or incases the spring and retains said spring normally in contact with the piston; it is provided in the sides thereof with ports positioned in such relation to the travel of the piston as to insure the inflow of the liquid material into the space below the piston as the latter is lifted; it is flanged and perforated at the top to afford a seat for the spring and to produce a port through which the liquid material, displaced by the upward travel of the piston, is free to flow out of the sleeve, and it is positioned in contact with a gasket adapted to serve as a seat for the piston when the latter is depressed by the spring, so that the sleeve retains the gasket in a predetermined position and precludes movement of said gasket with the piston as the latter travels within the sleeve.

The flanged closure or head is attached in any preferred way directly to the container, the latter being composed usually of glass. Said container is, or may be, provided at the bottom with a neck portion against which the flanged closure is fitted in a manner to embrace said neck portion, thereby affording protection to the fragile material. The connection between the closure and the container may be of a permanent nature or of a separable nature; but should the parts be separably connected, it is preferred to provide the container neck with a groove or grooves and the flanged closure with a stud or studs so as to coöperate as a bayonet lock, in which case a tight joint is secured between the container and the closure by the inter-

position of a gasket in order to preclude leakage.

Other features of the invention, and the advantages thereof, will appear in the course 5 of the following detailed description.

In the drawings:

Fig. 1 is a vertical section through the closure and the liquid-delivery device, the container being omitted for the sake of 10 clearness, and the piston being shown in its normal lowered position.

Fig. 2 is a vertical section, similar to Fig. 1, with the piston in a raised position so as to compress the spring, thereby placing the 15 piston in position for ejecting the liquid material on the downward movement.

Fig. 3 is a side elevation of the sleeve disconnected from the closure and the piston.

Fig. 4 is a plan of the sleeve. 20 Fig. 5 is a horizontal section through the sleeve on the line $x-x$ of Fig. 3.

Fig. 6 is a side elevation on a reduced scale of a portion of the glass container, illustrating one form of the neck portion thereof.

25 Fig. 7 is an inverted or bottom plan view of a part of the glass container shown in Fig. 6.

Fig. 8 is a plan view on a reduced scale of the closure and the delivery device shown in 30 Fig. 1.

Fig. 9 is a side elevation of the closure and the delivery device on the scale of Fig. 8.

A container for liquid material is indicated in Figs. 6 and 7 by the reference number 35 10, said container being provided at its bottom portion with a contracted neck 11. It is apparent that the container may be of any desired shape and size and, further, that it may be composed of any appropriate 40 material, such as glass.

12 designates a closure adapted to be applied to the neck 11 of the container for the purpose of tightly closing the opening in said neck of the container, thus precluding 45 the leakage of the liquid material from said container. The closure 12 is provided with a central depending boss 13 and with an up-standing flange 14, said boss and the flange being integral with the closure. It is preferred to make the closure with the flange and the boss from a single piece of sheet metal which is punched, spun, or otherwise treated so as to impart to the closure the form and dimensions illustrated in Figs. 1, 50 2, 8 and 9. The boss 13 is hollow or chambered and it depends centrally from the closure. The rim 14 extends upwardly from the closure at the edge portion thereof, the diameter of the rim exceeding the diameter 60 of the tubular boss.

The tubular boss 13 is provided with an inwardly extending flange 15 at the lower end thereof and in said flange 15 is provided an opening 16, the latter constituting the

liquid outlet, and through said liquid outlet 65 the liquid material is forcibly ejected by the action of a piston.

17 designates a sleeve, composed of sheet metal. The sleeve is preferably uniform in diameter, except that the top portion of the sleeve is provided with an inwardly extending flange 18 in which is formed an opening 19 adapted to serve as a vent through which liquid may flow freely on the upward travel of the piston, the liquid contained within the sleeve being displaced by the piston on said upward travel. The lower part of sleeve 17 fits snugly within the chambered boss 13, said sleeve 17 being fixed to said boss 13 in a suitable way. It is apparent that the sleeve may be soldered to the boss or it may be attached by a screw-thread thereto, but the detailed connection of the sleeve to the boss may be varied as desired.

The sleeve is provided in one or both sides thereof with vertical slots 20, the latter serving as ports to admit liquid freely to the space below the piston when the latter is in the raised position of Fig. 2, but when the piston is in the normal position, as in Fig. 1, said piston cuts off the flow of material into the space below it, whereby the piston acts in a threefold capacity; first, as a means for controlling the flow of liquid material into the space below the piston, as well as to provide for the inflow of air to the interior of the container body; second, as a means for forcibly ejecting the liquid thus admitted below the piston, and, third, as a valve for shutting off the outflow of the liquid material.

The piston 21 is composed of solid metal, preferably of a non-corrosive nature, and it is provided with an integral depending stem 22, the latter passing loosely through the opening 16 which constitutes the delivery port. The external diameter of the solid piston head 21 is slightly less than the internal diameter of the fixed sleeve 17, whereby the piston fits snugly within the sleeve and is free to move vertically therein. The external diameter of the rod 22 depending from the piston corresponds practically to the diameter of the liquid port 16, and when the piston and the rod occupy the raised positions of Fig. 2, said rod 22 practically closes the port 16, whereby the liquid material admitted into the space below the piston is precluded from flowing out through the port 16. The rod 22 thus acts as a valve to retain the liquid material in the space below the piston, and when the spring acts to depress the piston, the latter forcibly ejects the liquid material through the opening 16, at which time the liquid port is opened by a beveled or chamfered portion 23 provided on the surface of the stem 22, said chamfered portion 23 reducing the dia-

ameter of the upper portion of the stem so that the stem when the piston is lowered does not close the port 16, but, on the contrary, the chamfered portion 23 provides a 5 space between the surface of the stem and the edge of the liquid opening 16, through which space the liquid material is free to pass when said liquid material is acted upon by the piston on the downward travel 10 thereof.

24 designates a gasket positioned within the tubular boss and resting upon the in-turned flange 15 at the bottom of said boss. This gasket is composed of any suitable material and it forms a seat for the piston 21. 15 The under side of the piston is provided with a rib or flange 25, preferably tapering or V-shaped in cross section, said rib or flange being embedded within the material 20 of the gasket under the pressure of the spring 26 acting upon the piston. The tapering flange co-operates with the gasket 24 in securing a liquid-tight joint at the bottom of the delivery device, and thus the piston 25 acts in the capacity of a valve in cutting off the outflow of liquid and in precluding the leakage of liquid. In my prior patent 30 the gasket is liable to become displaced by the movement of the piston stem through it, 35 said gasket adhering to the piston stem and partaking of the movement thereof. In my present construction, however, this objection is overcome, for the reason that the gasket 24 is in contact with the lower edge of the fixed sleeve 17, said sleeve 35 acting to retain the gasket in a predetermined position and in contact with the flange 15 whereby the gasket cannot follow the movement of the piston stem.

40 The spring 26 is housed or incased within the upper part of the fixed sleeve, said spring being seated at its upper end against the in-turned flange 18 of said sleeve, whereas the lower end of the spring is in contact 45 with the piston for the purpose of forcibly depressing said piston, the pressure of the spring upon the piston being sufficient to force the tapering rib or flange 25 into firm engagement with the gasket 24.

50 It is apparent that the closure 12 is fitted to the neck 11 of the container in such manner that the flange 14 of the closure embraces the neck, thus imparting a desirable finish to the container and bringing the flanged closure 55 in such relation to the container that the metal of the closure affords protection to the fragile material of the container. The metal closure is adapted to be fastened permanently to the glass container by cementing the parts together, but when it is desired to 60 separately attach the closure to the container I employ a series of studs 27 on the flanged closure and a series of grooves 28 in the neck of the container. The grooves 28 are in-

clined slightly and open at one end through 65 the edge of the neck, as at 29. In connecting the closure to the neck the flange 14 is positioned so that the studs 27 will pass through the open ends 29 of the grooves 28, and thereafter the container and the closure 70 are moved rotatably so that the studs 27 will ride in the grooves 28 for the purpose of drawing the closure into engagement tightly with the neck. The edge of the container neck is seated upon a gasket 30 positioned 75 on the upper face of the closure 12, and within the flange 14 thereof, and by drawing the closure and the container together with a wedging action the gasket 30 is compressed between the edge of the container neck and the closure, thereby compressing the gasket and securing a tight joint which precludes leakage of the liquid material from the lower part of the container. 85

In the normal position of the parts the spring 26 acts upon the piston to depress it into contact with the gasket 24, the stem 22 depending a suitable distance below the tubular boss 13, thus exposing the stem 22 to convenient access, said piston 21 closing the lower end of the slots 20 in the fixed sleeve 17. To operate the piston, the hand is positioned, palm upward, below the stem 22, and by moving the hand upwardly the stem 90 and the piston are raised to the position of Fig. 2, the spring 26 being under compression. Upon such upward movement of the piston the stem 22 slides through the opening 16, whereby the stem acts to close said opening 16, and at this time the piston 22 is raised with respect to slots 20, whereby air is free to flow into the space below the piston so as to ultimately find its way into the interior of the container and at the same 100 time the liquid material in the container is free to flow through the slots 20 and substantially fill the space within the fixed sleeve 17 below the piston. With the parts 105 in their raised positions, the liquid fills the space below the piston and the stem 22 closes the aperture 16, thus precluding the outflow of the liquid material and retaining said liquid material in the path of the piston. By removing the hand pressure from the piston stem, spring 26 acts to quickly depress the piston and the stem, the chamfered part 23 of the stem opening the liquid outlet 16, whereby the piston exerts pressure 115 upon the liquid during the downward movement of said piston under the action of the spring, as a result of which a limited predetermined quantity of liquid is forcibly ejected into the palm of the hand, i. e. the latter is spattered upon the hand so as to become spread or diffused over it. 120

It is apparent from the description taken in connection with the drawings that the

closure and the sleeve can be manufactured rapidly and economically from punched, stamped, pressed or spun sheet metal. Furthermore, the parts are simple in construction, easily and quickly assembled, and practical experience shows that the device is efficient and reliable in operation.

Having thus fully described the invention, what I claim as new, and desire to set 10 cure by Letters Patent is:

1. In a liquid dispensing device, the combination of a closure provided with a depending boss, a sleeve extended within and attached to said boss and extending upwardly from the closure, a valve seat positioned within the boss below and engaged by the end of said sleeve, a valve provided with a stem and slideable within the sleeve, and means for depressing the valve into contact with the valve seat.

2. In a liquid dispensing device, the combination of a closure provided with a depending boss, a sleeve extended within and attached to said boss and extending upwardly from the closure, said sleeve being provided at its upper end with a liquid opening and provided below said opening with a liquid inlet, a valve seat positioned within the boss and engaged by the end of said sleeve and operating to depress the valve into contact with said seat, said valve operating upon the upward movement thereof to permit the flow of liquid through said liquid inlet into the space below the valve.

3. In a liquid dispensing device, the combination with a closure provided with a depending boss, a sleeve extended within and attached to said boss and extending upwardly from the closure, a valve seat composed of soft material and positioned within the boss below and engaged by the end of said sleeve, a valve provided with a stem and slideable within the sleeve, and means for depressing the valve into contact with the valve seat.

4. In a liquid dispensing device, the combination of a closure member provided with a chambered boss and with a liquid outlet, a valve seat independent of the closure member and the boss and having an opening in register with the liquid outlet, a valve provided on its under surface with a rib, a depending stem for said valve slideable in the opening of the valve seat, means for retaining the valve seat against displacement by the sliding movement of the valve through it, and means for depressing the valve with its rib into forcible contact with the valve seat.

5. In a liquid dispensing device, the combination of a closure member provided with a chambered boss and with a liquid outlet, a valve seat composed of soft material and

provided with an opening in register with the liquid outlet, a valve provided on its under surface with a rib and provided, also, with a depending stem, said stem being slideable in the opening of the valve seat and in the liquid outlet, means for retaining the valve seat against displacement by the sliding movement of the stem through it, and means for depressing the valve into forcible contact with the valve seat so as to embed the rib of said valve into the soft material of the valve seat.

6. In a liquid dispensing device, the combination of a closure provided with a liquid outlet, a gasket seated on said closure adjacent said outlet, a piston valve having a stem slideable through the gasket and the liquid outlet, a sleeve contacting with said gasket and retaining the latter in position, whereby the gasket is precluded from displacement by the action of the stem thereon, said sleeve coöperating with the piston valve to direct the movement thereof, and a spring retained by the sleeve in coöperative relation to said piston valve.

7. In a liquid dispensing device, the combination of a closure provided with a liquid outlet, a gasket seated on said closure adjacent said outlet, a piston valve having a stem slideable through the gasket and the liquid outlet, said piston valve being provided with a flange positioned for contact with said gasket, a sleeve contacting with said gasket and coöperating with said piston valve, and a spring retained by the sleeve in contact with said piston valve, whereby the spring exerts pressure upon the piston valve for embedding the flange thereof in the material of the gasket.

8. In a liquid dispensing device, the combination with a container, and a closure provided with a liquid outlet, of a sleeve attached to said closure and extending upwardly within the container, said sleeve being provided with a slot forming a liquid inlet to the chamber of the sleeve, a valve seat within the closure engaged by the inner end of said sleeve, a liquid controlling and ejecting piston provided with a depending stem, said piston having frictional contact with the sleeve and adapted to be raised relatively to the slot therein for permitting the flow of liquid into the space below the piston, and a spring for depressing the piston within the sleeve, said depending stem being slideable in the liquid outlet and the cross sectional dimensions of the stem for a part of its length conforming to the area of the liquid outlet so that upon the elevation of the piston and the stem the latter closes the liquid outlet against the premature outflow of the liquid material.

9. In a liquid dispensing device, the combination with a container, and a closure pro-

vided with a liquid outlet, of a sleeve attached to said closure, said sleeve being provided with a liquid inlet, a valve seat within the closure engaged by the inner end of said sleeve a double valve member, one part of said valve member operating within the sleeve to open the liquid inlet for the liquid material to flow into the space within the sleeve below said valve member, and at the same time the other part of said valve member operating in the liquid outlet to close the latter against the outflow of the liquid

material, and a spring coöperating with the double valve member so as to forcibly eject the liquid material upon the descent of the 15 double valve member.

In testimony whereof I have signed my name to this specification in the presence of two subscribing witnesses.
